Primary Examiner — Ian Simmons*Assistant Examiner* — Mark Cavanna(74) *Attorney, Agent, or Firm* — Labatt, LLC(57) **CLAIM**

The ornamental design for an electrode, as shown and described.

DESCRIPTION

FIG. 1 is a perspective view of an electrode according to the present design.

FIG. 2 is a rear elevation view of the electrode shown in FIG. 1.

FIG. 3 is a left elevation view of the electrode shown in FIG. 1.

FIG. 4 is a top plan view of the electrode shown in FIG. 1.

FIG. 5 is a right elevation view of the electrode shown in FIG. 1.

FIG. 6 is a front elevation view of the electrode shown in FIG. 1; and,

FIG. 7 is a bottom plan view of the electrode shown in FIG. 1.

The broken lines illustrate portions of the electrode that form no part of the claimed design.

1 Claim, 3 Drawing Sheets(56)
